UNITED STATES PATENT OFFICE.

WILLIAM A. DANIELSEN, OF PALATINE, ILLINOIS.

FLUSH-TANK VALVE.

1,269,163.

Specification of Letters Patent. Patented June 11, 1918.

Application filed January 26, 1916. Serial No. 74,321.

To all whom it may concern:

Be it known that I, WILLIAM A. DANIELSEN, a citizen of the United States, residing at Palatine, in the county of Cook and State of Illinois, have invented certain new and useful Improvements in Flush-Tank Valves, of which the following is a specification.

My invention relates to flush tank valves, and the object thereof is to furnish a simple, effective and durable device of that description. The valves of this kind in general use are provided with hinged or pivoted parts, which are subject to wear and not easily replaced. In applying the principles of my invention I do away with wearing parts, make a simple, noiseless and effective mechanism, which cannot break, wear out or get out of order, and I moreover provide a seat in which the elastic portion can be readily replaced without the exercise of mechanical skill, with simple tools and at practically no expense.

The principles of my invention are illustrated in the drawings in which—

Figure 1 is a top view thereof.

Fig. 2 is a side elevation partially in section.

Fig. 3 shows a modification of the device. Further describing my invention with reference to the drawings: 1 is the bottom, and 2 the sides of a flush tank. The outlet casing 3 of my improved valve is preferably integrally formed, and the threaded portion 4 is extended downwardly through the tank bottom. A gasket 5 is interposed between the shoulder 6 and the bottom 3 of the tank, and the whole is secured in place by the nut 7 to form a fluid tight joint. The upper part of the casing is broadened to form an annular flange 8, and has an off-set elbow 9, to which is attached the overflow pipe 10. An annular groove 11, is connected with said elbow and provides means by which overflow from the tank through pipe 10 may be conducted to the waste pipe without its movement being interfered with by the valve head. An annular gasket 12 is placed on the flange 8 and held securely in place by

the ring 13, which may be clamped thereon by screws 14. The inner edges 15 of said gasket are turned downwardly to form an annular seat for the valve head 16. The latter should be buoyant, and to this end may be a sealed body of hollow metal, although I prefer to make the same as indi-

cated with the flat top 17 and slanting sides 18, leaving the bottom 19 open as indicated. This is not necessary, and such bottom may be closed if desired. I further prefer the form in vertical section of the frustum of an inverted elongated cone. The flat top when the valve is closed gives the best action thereon of the water to close the valve head on its seat, while, when raised, the flow of water on the slanting sides of the cone tends to hold the same open. A valve stem 20 is extended upwardly from the head 16, and passes through a bifurcated bracket guide 21, which may be attached to the waste pipe. A chain or lever may be attached to the eye 22, at the upper part of the stem, whereby the valve may be tripped when it is desired to empty the tank. It will be seen that, when the valve is unseated, the buoyancy of the floating head, together with the action of the water on the slanting sides of said head, will cause the valve to remain unseated until the water has flowed out of the tank to the upper level of the ring 13, whereupon the valve will again seat itself and the tank will be again filled by means of the ordinary inlet valves which are well known in the art. It will be further noted that the open mouthed form of valve head is not buoyant except when sufficiently raised that the water closes the underside, thereby sealing the air within it. When in its seat or closely approximated thereto, the absence of water underneath to seal the mouth causes the valve head to close with its whole weight, thereby sealing itself more readily and effectively.

A modification of my device is shown in Fig. 3, in which the flange 8' is internally threaded to take the peripherally threaded ring 13'. If desired a plurality of supports 25 may be attached to said ring and extended upward thereon and closed at the top 100 to form a cage which will act as a guide for the valve stem and head.

Having thus fully described my invention what I claim as new and desire to secure by Letters Patent is—

1. A flush tank valve comprising an outlet casing having a seat provided with an upwardly extended annular flange and an internally threaded rim on said flange, an elastic annular member seated on said flange and having a depending flap, a peripherally threaded ring for securing said

- elastic member within the said rim, a closure consisting of a hollow head in the form of an inverted truncated cone provided with an air opening on the underside thereof, and a cage attached to said ring and adapted to guide said closure with reference to said seat.
2. A flush tank valve comprising an outlet casing having a substantially cylindrical bore and provided with an annular flange on the upper end thereof, an elastic annular member seated on said flange and having a depending annular flap lying against the wall of said bore, means for attaching the elastic member to the flange, and a float valve in the form of a hollow inverted frustum of an elongated cone having a closed base and adapted to seat within said casing and the flap of said elastic member.
3. A flush tank valve comprising an outlet casing having a substantially cylindrical bore and provided with an annular end flange an elastic annular member secured on said flange and having a depending annular edge conformed to the wall of the bore to form a valve seat, and a hollow closure head in the form of a frustum of an elongated inverted cone having a closed base and adapted to seat within the casing and the depending edge of the elastic member.
4. A flush tank valve comprising a closure consisting of a hollow head in the form of a frustum of an elongated inverted cone having a closed base and open at its small end, an outlet casing having a bore whose wall is substantially cylindrical, and an annular elastic gasket secured upon the upper end of said casing and having its inner edge turned downwardly against the wall of the bore of the casing, the tapered wall of
- said head being adapted to engage within the downturned edge of the gasket when the valve is closed.
5. A flush valve comprising a chambered casing through which water is adapted to flow, a cylindrical rubber valve seat having an annular flange, means for clamping the flange tightly against the valve casing, and a hollow valve adapted to enter the seat and engage the cylindrical portion thereof.
6. A flush valve comprising a chambered casing through which water is adapted to flow and having an internally threaded flange at its top, a ring screwing into the flange, a rubber valve seat of annular form of less diameter than the ring and having an annular flange clamped between the ring and valve casing, and a rigid hollow valve engageable internally of the seat.
7. A flush valve comprising a chambered casing through which water is adapted to flow and having an internally threaded flange at its top, a ring screwing into the flange, a rubber valve seat of annular form of less diameter than the ring and having an annular flange clamped between the ring and valve casing, and a rigid hollow valve engageable internally of the seat, said ring having a cage extending upwardly therefrom for guiding the hollow valve and forming a handle for the screwing and unscrewing of the ring.
- In witness whereof, I have hereunto subscribed my name this 11th day of December, 1915, in the presence of two subscribing witnesses.
